US00D884682S

(12) **United States Design Patent** (10) **Patent No.:** **US D884,682 S**
Du (45) **Date of Patent:** **** May 19, 2020**

(54) **EARPHONES**

(71) Applicant: **DONGGUAN PINMI ELECTRONIC TECHNOLOGY CO., LTD**, Dongguan (CN)

(72) Inventor: **Zhanyuan Du**, Kaifeng (CN)

(73) Assignee: **DONGGUAN PINMI ELECTRONIC TECHNOLOGY CO., LTD**, Dongguan (CN)

(**) Term: **15 Years**

(21) Appl. No.: **29/721,231**

(22) Filed: **Jan. 18, 2020**

(51) **LOC (12) Cl.** **14-01**

(52) **U.S. Cl.** **USPC D14/223**

(58) **Field of Classification Search**

USPC D14/223, 205; D24/174; 381/380; 455/90.3, 575.1, 569.1
 CPC H04R 1/10; H04R 25/00; H04R 1/1025; H04R 1/1066; H04R 1/1016; H04R 5/033; H04R 5/0335; B65D 25/10

FOREIGN PATENT DOCUMENTS

EM 007525092-0002 * 1/2020

Primary Examiner — Paula Allen Greene

(57) **CLAIM**

The ornamental design for earphones, as shown and described.

DESCRIPTION

FIG. 1 is a perspective view of earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the earphones where the earphones are received in a case.

The broken lines in the drawings depict portions of the earphones that form no part of the claimed design.

1 Claim, 9 Drawing Sheets
